UNITED STATES PATENT OFFICE.

BENJAMIN F. STAUBER, OF SPOKANE, WASHINGTON.

WATER-ELEVATOR.

1,241,297.

Specification of Letters Patent. Patented Sept. 25, 1917.

Application filed July 10, 1914. Serial No. 850,178.

To all whom it may concern:

Be it known that I, BENJAMIN F. STAUBER, a citizen of the United States, and a resident of Spokane, in the county of Spokane and State of Washington, have invented certain new and useful Improvements in Water-Elevators, of which the following is a specification.

My invention relates to the utilization of the power of currents of rivers, creeks, and other moving bodies of water, to operate suitable machinery, in the present case a pump, and the main object thereof is to provide such a device which is adapted to 10 be anchored in a stream and to be so set in such position as to avail itself of the flow of water in such stream; a further object is to provide a water-wheel arrangement which may be adjusted to meet conditions 15 and a further object is to provide such wheels with relatively great leverage to correspondingly affect the connected pump or other machinery; a further object is to provide a pump in connection with such a device which raises water from the stream to 20 any desired place on the shore thereof, and the pumping of which is continuous rather than by impulses or pulsations; a further object is to provide a plurality of eccentric pistons in said pump and alternately operating 25 to pump water but in such manner as to make the said pumping continuous; a further object is to provide a movable bulk-head for each of the pistons, to take the strain of the water in the pumping operation, and to take such strain or pressure in 30 such manner as not to interfere with the movement of said bulk-heads; but, rather, being assisted thereby and thus reduce friction and wear to a minimum; and further 35 objects are to provide such devices which are simple in construction, installation, and operation, which require no attention whatever after being set, which are readily adaptable to streams and shorelines of varying 40 character, which are very powerful, and which are comparatively inexpensive.

My invention is fully described in the following specification, of which the accompanying drawings form a part, in which the same parts are designated by the same reference characters in each of the views, and in which:

Figure 1 is a view of my invention in use; 55 Fig. 2 is an enlarged, fragmentary, plan view thereof;

Fig. 3 is a section, greatly enlarged, on the line 3—3 of Fig. 4;

Fig. 4 is a similar section on the line 4—4 of Fig. 3; 60

Fig. 5 is an enlarged section through my pump and on the line 5—5 of Fig. 6;

Fig. 6 is a section on the line 6—6 of Fig. 5; and

Fig. 7 is an enlarged side view of an anchor I employ. 65

In the drawings forming a part of this application I have shown a float 10, supported by buoys or barrels 11, and having trusses 12 thereon supporting a platform 70 13 pivoted at 14 to said trusses, roller bearings 15 being mounted in a dependent frame 16 adjustably held by means of a threaded rod 17 pivoted thereto at 18 and rotatable in a support 19 on one of the truss members 75 12, a hand-wheel 20 being provided for said rod, and also pivotally mounted at 14 are two anchor arms 21 pivotally connected at 22 to concrete or other suitable anchors 23 on the shore of a stream, as clearly shown in 80 Fig. 1.

Secured above the platform 13 is a plate 24 carrying vertically arranged roller bearings 25 for a vertical shaft 26 also guided by the bearings 15, and said shaft carries 85 two spaced hub-plates 27 and 28 supporting wheel spokes 29 provided, each, with a blade 30 at its outer end, said spokes being preferably made of adjustable lengths, and a cage of rollers 31 is arranged between the plates 90 24 and 28, as clearly shown in Figs. 3 and 4, and I also provide vertical braces 32 and horizontal braces 33 for the said spokes 29.

The shaft 26 carries a bevel gear 34 enmeshed with a gear 35 on a shaft 36 supported in the frame 16, and which shaft also carries a sprocket 37 connected, by means of a chain 38, with a sprocket 39 on a pump 40, whereby said pump may be actuated by the water-wheel formed by the spokes and 100 blades above described.

The pump 40 comprises a casing divided into two cylindrical chambers 41 and 42, and two compartments 43 and 44 formed by a partition 45, Fig. 5, the chamber 43 having 105 a pipe 46 in flexible connection therewith and which is extended to the shore of the stream, Fig. 2, and said chamber 43 is connected with the floor of the frame 16, as shown in Fig. 4, whereby the pump moves 110 with the said frame when adjusted by means of the rod 17, and said pump is arranged

beneath the float 10 in such manner as to be always submerged in the stream.

The cylindrical chambers 41 and 42 have a port 47 and 48, respectively, leading into the chamber 43 and controlled by ball-valves 49 to prevent any water in the chamber 43 from passing into the cylindrical chambers, and each of said last named chambers has a hollow and open-ended shaft 50 and 51, respectively, therein provided, each, with respective ports 52 and 53, meshing spur-gears 54 and 55, to the former of which shafts, 50, the sprocket 39 is secured, as shown in Fig. 6, and each of the shafts 50 and 51 has an eccentric piston 56 and 57, respectively, extending the full length of the cylindrical chambers 41 and 42 in which they revolve, and which pistons have a nose-plate 58 outwardly forced against the walls of the respective cylindrical chambers by means of springs 59, to take up frictional wear.

Within the chamber 44 are two arms 60 and 61 pivoted at 62 and 63 and provided with bulk-heads 64 and 65, respectively, passing into the chambers 41 and 42 through slots 66 and 67, respectively, and normally forced thereinto by means of a spring 68, or equivalent, said bulk-heads being alternately forced outwardly by the respective eccentric pistons in their revolution, against the action of the spring 68, said pistons being simultaneously revolved by the meshed gears 54 and 55.

The pistons are set so that one is farthest from the outlet port of the corresponding cylindrical chamber when the other piston is crossing the outlet port of the other chamber, whereby continuous pumping results or, rather, continuous flow, the water admitted to each piston chamber through its hollow shaft being forced through the corresponding outlet port because of the pivoted bulk-head therein and which bulk-heads always impinge against the corresponding piston, although they are forced entirely out of corresponding piston chambers by said pistons in each revolution of the latter, and the method of mounting said bulk-heads absolutely prevents any friction thereof with the walls of the slots in which they operate, this being an important factor of my invention and, when water has once been forced into the pipe 46, no return thereof is possible to the piston cylinders, and said water is, therefore, forced to the point of use.

It will thus be seen that I provide a stream current motor of great power, adjustable to meet varying conditions, movable with respect to tides, practically frictionless, and delivering a constant flow of water, the device being reversible for use on opposite stream banks by the mere changing of the sprocket 39 from one shaft to the other, or both may be provided with such a sprocket

and then the chain alone would require change from one to the other.

The individual bulk-head construction permits either or both of them to be worn down to a point where they no longer reach their respective pistons, without impairment to the other bulk-head, and this is highly important as it tends to a long life to the pump; I may, also, employ only one pumping cylinder where a small delivery is required, but this delivery will be in pulsations; the piston ports are so located, adjacent the extreme radius of the pistons, that a constant supply of water is assured through centrifugal action as well as the partial vacuum occasioned by the revolution of the pistons; the float, when employed, is maintained at a desired distance from the bank of the stream and immovable by the currents, the changing elevations of the float, due to the rise and fall of the tides, not affecting the adjustment of the water-wheel with respect thereto, and with the surface of the stream, suitable cables being employed, if desired, to insure such float position; the water-pipe is formed, by rotary connections, so that it is never strained in the rise and fall of the float, and the entire device is practical, efficient, automatic, simple, and comparatively inexpensive.

While I have shown a pump actuated by the water-wheel, it will be apparent that the movement of said wheel may be transmitted to the shore to operate saws, churns, or other machinery and, reserving the right to make all desired changes in and modifications of the form shown and described, what I claim as new, and desire to secure by Letters Patent, is:

1. A device of the class described, comprising a floating support, a frame pivotally and adjustably hung thereon, a shaft in said frame, a water-wheel carried by said shaft, a pump carried by the frame and projecting through the said support, means for operating the pump from said shaft, and means for locking said frame in desired position to submerge a portion of said water-wheel, and maintain said pump in submerged position.

2. A device of the class described, comprising a floating support, a frame pivotally and adjustably hung thereon, a shaft in said frame, a water-wheel carried by said shaft, a pump carried by the frame and projecting through the said support, means for operating the pump from said shaft, a pipe communicating said pump with the shore of a stream, means for maintaining said float in position with respect to said shore, and means for locking said frame at a desired angle to submerge said water-wheel, at one side thereof, and maintain said pump in submerged position, said pipe being of flexible construction to accommodate the

same to the vertical tidal movement of said float.

3. A device of the class described, comprising an apertured float having upwardly extending members, a frame pivoted to the upper ends of the said members, a pump carried by the frame and extending through the aperture of the float, a shaft mounted in the frame and projecting above the same, 10 a water wheel mounted on the upper end of the shaft, gearing between the pump and shaft, and means for adjusting the frame with respect to the support whereby to submerge the water wheel and maintain the 15 pump in submerged position.

4. A device of the class described, comprising a float having upwardly extending members, a frame pivoted to the upper ends of the said members, a shaft mounted in 20 the frame and projecting above the same, a water wheel on the upper end of the shaft, rollers between the hub of the wheel and

the top of the frame, a pump, means for operating the pump from the said shaft, and means for adjusting the said frame 25 with respect to the float.

5. In a device of the class described, a float having upwardly extending members, a frame pivoted to the upper ends of the said members, a screw pivoted to said frame 30 and mounted in a support carried by one of the members of the float and having a hand wheel mounted thereon, a water wheel mounted on said frame, a pump, and means for operating the pump from the shaft of 35 the water wheel.

In testimony whereof I have signed my name to this specification in the presence of the subscribing witnesses.

BENJAMIN F. STAUBER.
